ROLLING MILL

Howard H. Talbot, Pittsburgh, Pa., assignor to United Engineering and Foundry Company, Pittsburgh, Pa., a corporation of Pennsylvania

Filed Apr. 30, 1959, Ser. No. 810,099

1 Claim. (Cl. 80—38)

This invention relates to rolling mills employed in the reduction of metallic strip-like material and particularly to a mill adapted to produce a rolled product characterized by having a substantially uniform cross-sectional thickness across the width thereof.

In the use of present-day mills, experience has shown that it is very difficult to produce a strip having a uniform thickness across its width primarily by reason of the inherent deflection of the working or metal engaging rolls of the mill. On being subjected to the forces during rolling which tend to separate the rolls, the rolls act somewhat the same as beams supported at their ends and subjected to a substantially uniform load distributed along most of the length thereof, the distance over which the uniform load acts being of course, dependent upon the width of strip material being processed. As in the case of a structural beam, the rolls are subjected to the greatest deflection at their centers. Where the same reduction is to be taken, for example, in one mill having small diameter work rolls and in another mill having large diameter work rolls, the small diameter rolls will have imposed upon them a separating force less than that to which large diameter rolls are subjected. However, the small diameter rolls, as will be apparent, also resist bending less than do large diameter rolls.

In order to overcome the difficulties which are to be expected when mills are employed having work rolls of small diameter and without sacrificing the advantages to be gained by using such rolls, modern mills are provided with a large diameter backing-up roll for each work roll, the axes of which are arranged in the same vertical plane as those of the work rolls and the surfaces thereof in frictional contact throughout the roll body length. This type of mill is commonly referred to as a four-high mill. The larger diameter rolls, though they are in supporting engagement with the work rolls along the entire length of the roll body, resist but do not completely nullify the bending forces set up in the mill during normal operation thereof. Thus, even with the increased rigidity provided by the large diameter back-up rolls, there will be at times substantial bending or deflection not only of the back-up rolls but, of more importance, the work rolls as well, so that if the rolls are crowned, the crown will be exceeded by the deflection of the rolls caused by the rolling loads imposed thereon. In mills where the rolls are of substantial length, the magnitude of the flexing or bending is quite pronounced so that the rolled product will be characterized with a definite variation in thickness across the width.

In an effort to compensate for the deflection of the work rolls and/or the backing rolls, both of the work rolls and/or both of the back-up rolls are crowned or cambered, i.e., ground in such a fashion that the diameter of the roll gradually increases from the ends to the center. It will be appreciated that the extent of the crown formed on the rolls will vary widely by reason of the variable conditions under which mills employing such rolls may be required to operate. The extent of the crown will depend

2

upon the type of mill, length of rolls, metallurgical characteristics of the strip material being reduced, the pressures imposed upon the mill, the width of strip, the thermal conditions and the amount of reduction to be taken. Since the crowning of the rolls is determined primarily on the basis of but one combination of these variables, it is apparent that the crown will not be wholly satisfactory for any other combinations of those variables as may be encountered. When conditions of rolling are to be varied from one combination to another, then, in order to provide a substantially flat pass, the rolls in the mill must be replaced with other rolls having a different crown.

With the foregoing in mind, it is one of the objects of this invention to provide a rolling mill which is constructed in such a fashion that the rolls of the mill will be so supported and the crown thereof so controlled that a substantially uniform pass between the work or processing rolls will be maintained during a rolling operation thereby to produce a rolled product having a substantially uniform thickness across its width.

It is another object of this invention to provide a mill having small diameter work rolls each supported substantially along the entire length of the roll body by back-up rolls, which in turn are supported in an area adjacent to the central portion thereof by relatively large diameter short bodied rolls, the degree of support offered by such rolls being determined by the degree of the crown for which control is to be provided.

A further object of this invention is to provide a rolling mill having back-up and working rolls in which crowns are formed either on one or both of the working rolls and/or on one or both of the backing rolls in which there is included a relatively large diameter short-bodied supporting roll for engaging with each of the back-up rolls thereby to restrict the deflection of the back-up rolls and, hence, augment or control the effect of the crown on the rolls so that the crown will be made effective over a relatively wide range of rolling conditions for producing a product of uniform thickness irrespective of the width thereof.

Still another object of this invention is to provide controlled variable pressure applying means in contact with and by which pressure may be exerted upon each of the back-up rolls of a four-high mill to limit the deflection of the rolls and, hence, control the crown thereof over a wide range of rolling conditions to which the mill may be subjected and thus provide a substantially uniform pass between the work rolls.

These objects, as well as the various other novel features and advantages of this invention, will be apparent from the following description and accompanying drawings of which:

Fig. 1 is an end elevation view of a mill in which there are embodied the features of the invention herein disclosed;

Fig. 2 is a side sectional elevation view taken on line II—II of Fig. 1, and

Fig. 3 is a side sectional elevation view similar to Fig. 2 in which the invention is embodied in modified form.

With reference to Figs. 1 and 2, there is illustrated therein a mill which comprises a pair of housings 11, secured together at the top and bottom by separators 12 and 13 respectively, and in which there are included a pair of work rolls 14, a back-up roll 15 in engagement with and for supporting the upper work roll and a back-up roll 16 for supporting the lower work roll. The work rolls are supported at their ends in suitable bearing-chock assemblies 17, one end of each roll being extended and to which a coupling 18 is secured for driving the rolls. The ends of the upper back-up roll 15 are

mounted in bearing-chock assemblies 19 which are engaged by suitable screws 21 which are threaded in the upper portions of the housing and actuated by a worm gear drive 22 within which the upper portions of the screws are received and slidably engaged in suitable splines 23. The lower back-up roll 16 is supported at its ends in suitable bearing-chock assemblies 24 which, in turn, rest on the housing at the bottom of the windows.

At the central body portion or area of the upper back-up roll 15, and in engagement therewith, there is a relatively large diameter short-bodied supporting roll 25 secured at its ends in bearings 26 within a frame 27 confined and slidably guided for vertical movement between the housings 11 and urged normally in an upward direction by a piston cylinder assembly 28 connected to the frame 27 and to the separator 12. The ends of the frame 27 are engaged by pistons 29 which extend downward from cylinders 31 mounted within openings in the upper separator 12.

In engagement with the central body portion or area of the lower back-up roll 16, there is a relatively large diameter short-bodied supporting roll 32 which is mounted in suitable bearings 33 within a frame 34. The frame 34 is confined and slidably guided for vertical movement between the housings 11 and normally urged in an upward direction by a pair of pistons 35 extending upward from cylinders 36 mounted within the lower separator 13.

Fluid at a controlled variable pressure is supplied to each of the piston cylinder assemblies 29, 31 and 35, 36 through suitable piping 37 connected to a controllable variable pressure pump 38 connected to a source of fluid, not shown, which is driven by a variable speed motor 39.

Depending upon the crown of either or both of the work rolls 14 and/or either or both of the back-up rolls 15 and 16, pressure supplied by the pump 38, which is variable over a wide controllable range, will be of sufficient intensity to cause the pistons 29 and 35 respectively to exert the proper pressure upon the back-up rolls adjacent thereto thereby to supplement the effect of the crown on the roll or rolls so that during a reducing operation a substantially uniform pass will be maintained between the work rolls.

As shown in Fig. 1, suitable roll balancing piston cylinder assemblies 41 are provided between the bearing-chock assemblies 19 and 24 of the back-up rolls and similar assemblies 42 are provided between the bearing-chock assemblies 17 of the work rolls.

Fig. 3, which represents a modified embodiment of the invention disclosed herein, includes a mill having a pair of housings 51 secured together by upper and lower separators 52 and 53 respectively, a pair of work rolls 54 and upper and lower back-up rolls 55 and 56 respectively in contact therewith. The work rolls 54 are supported at their ends in suitable bearing-chock assemblies 59 and the back-up rolls supported in suitable bearing-chock assemblies 61 and 62 respectively, the bearing-chock assemblies being free to move vertically within the windows formed in the housing.

In lieu of the screwdown mechanism employed in the preferred embodiment of invention illustrated in Figs. 1 and 2, the means for applying pressure to the ends of the upper back-up roll during a rolling operation comprises a pair of piston cylinder assemblies having cylinders 63 which are supported in the separator 52 and piston rods 64 extending downwardly therefrom and engaged with the bearing-chock assemblies 61. Suitable roll balancing piston cylinder assemblies, though not shown specifically, are provided which are similar to those included in the preferred form of invention as shown in Fig. 1. A controllable pressure pump 65, driven by a variable speed motor 66, delivers fluid at the proper pressure to the cylinders 63 through piping 67 connected therebetween.

In contact with the central body portion or area of the upper back-up roll 55, there is a relatively large diam-

eter short-bodied roll 68 mounted at its ends in suitable bearings 69 within a frame 71 guided for vertical movement between the housings. The frame 71 is urged normally in an upward direction by a piston cylinder assembly 72 connected to the frame 71 and to the separator 52. The ends of the frame 71 are engaged by pistons 73 which extend downward from cylinders 74 mounted within suitable openings in the upper separator 52.

Engaged with the lower back-up roll 56, there is also a relatively large diameter short-bodied roll 75 which is mounted at its ends in suitable bearings 76 supported in a frame 77. The frame 77 is guided for vertical movement between the housings 51 and is normally urged in an upward direction by a pair of pistons 78 extending upwardly from cylinders 79 mounted in suitable openings in the lower separator 53. Fluid at controlled variable pressure is supplied to the cylinders 74 and 79 through suitable piping 81 connected to a controllable variable pressure pump 82 connected to a source of fluid, not shown, which is driven by a variable speed motor 83.

As mentioned heretofore, depending upon the material to be reduced, the reduction to be taken, the width of material and the metallurgical characteristics of the material, pressure is supplied to the back-up rolls by actuating the screws 21 of the preferred embodiment or by applying the desired pressure to the cylinders 63, of the modified embodiment, thereby to press the back-up rolls into engagement with the work rolls to establish the pass between the work rolls. During a strip reducing operation, the work rolls and the back-up rolls tend to bend outward at their centers and thus tend to create a pass wider at the center than at the edges. For a given crown on some or all of the rolls, and without more, a flat pass can be obtained as the rolls bend outward for one condition of rolling only. However, by means of the relatively large diameter short-bodied rolls 25, 32, 68 and 75 by which controlled pressures may be imposed on the back-up rolls, additional resistance to bending of the back-up rolls and, consequently of the work rolls as well, is provided thereby augmenting or controlling the crown of the rolls so that a uniform pass between the work rolls over a wide range of rolling conditions is established. Merely by controlling the pressure supplied by the pumps to the cylinders 31, 36, 74 and 79, a given crown on any or all of the rolls of the mill may be made most effective over a wide range of operating conditions whereby a uniform pass between the work rolls may be readily established and maintained irrespective of the reducing operations being carried out. Thus, the necessity of changing to rolls having a different crown each time a new rolling condition presents itself is avoided.

Though this invention has been described as being embodied in a mill of which one or more of the rolls are crowned, it is to be appreciated that even though none of the rolls is crowned, the control effected by this invention is of a character to offset the camber normally imposed upon the rolls during a strip reducing operation.

In accordance with the provisions of the patent statutes, I have explained the principle and operation of my invention and have illustrated and described what I consider to represent the best embodiment thereof. However, I desire to have it understood that within the scope of the appended claim, the invention may be practiced otherwise than as specifically illustrated and described.

I claim:

A mill within which a flat rolling pass is maintained for reducing strip of various widths continuously to form a strip of a substantially uniform thickness across the width thereof comprising a housing, a pair of relatively small diameter work rolls between which the strip to be reduced is passed, a pair of relatively large diameter back-up rolls for contacting and supporting said work rolls, a crown related to a given width of strip to be reduced and formed on at least a pair of said aforementioned rolls to provide

a flat pass for reducing strip of said given width, a relatively large diameter relatively short-body roll in contact with the central zone of each of said back-up rolls, a piston cylinder assembly operably connected to each of said short-body rolls for applying to said back-up rolls a force in a direction and of a controlled magnitude to supplement the effect of said crown when reducing strip of said given width when required and when reducing strip of width greater than said given width and means connected to and for establishing a controlled variable pressure adapted to be increased in intensity within said piston cylinder assembly in connection with an increase in width of strip beyond said given width thereby to resist outwardly bowing and maintain a flat rolling pass under conditions imposed upon the rolls by the increased width 10 of strip. 15
